Primary Examiner — Doris Clark

(57) **CLAIM**

I claim the ornamental design for the personal fire escape ladder, as shown and described.

DESCRIPTION

FIG. 1 is a front view of the personal fire escape ladder.

FIG. 2 is a rear view of the claimed design.

FIG. 3 is a top view of the claimed design.

FIG. 4 is a bottom view of the claimed design.

FIG. 5 is a left side view of the claimed design; and,

FIG. 6 is a perspective view of the claimed design.

The rails of the personal fire escape ladder are broken to indicate indeterminate length of the personal fire escape ladder.
